ARTICLE HOLDER

Charles E. Berg, Watertown, N. Y.

Application December 20, 1932, Serial No. 648,102

6 Claims. (Cl. 24—249)

This invention is a device for supporting brooms, brushes or other handled articles in proximity to a wall or like surface.

One of the objects of the invention is to provide a simple device which may be readily secured to a wall or other supporting surface, and having means for engaging the handle of a brush, broom or other handled device, in such manner as to hold it in a suspended position. A further object is to provide a device of the character mentioned, so constructed and arranged that the weight of the supported article is utilized to prevent swinging thereof. A further object is to provide a supporting device with respect to which the article to be supported may be readily engaged or disengaged.

The invention will be hereinafter fully set forth and particularly pointed out in the claims.

In the accompanying drawing:—

Figure 1 is a front elevation illustrating one form 20 of a supporting device constructed in accordance with the invention. Figure 2 is a longitudinal sectional view. Figure 3 is a top plan view. Figures 4, 5 and 6 are similar views of a slightly modified form.

Referring to Figures 1, 2 and 3 of the drawing, 25 10 designates a metal plate-like, support-member, having beveled marginal edges 11, and secured to a wall W or other similar supporting surface by means of a screw 12, passed through a suitable 30 opening in said member. The lower edge of the member 10 is cut away as indicated, to form a slot 13, the end walls of which are bent at right angles to form hinge ears 14. The corners 11^a are sharpened to penetrate wall W.

The article-supporting member consists of a 35 metal plate-like body 15, having beveled edges 16, and a handle-receiving opening 17. The rear end of the body 15 is provided with a reduced lug 18, the sides of which are bent downwardly to form 40 hinge ears 19. It will be observed that the ears 19 lie between the ears 14, and that said ears are provided with registering perforations to receive the hinge pintle 20. One of the flanges 11 of the body 10 is provided with an opening 21 through 45 which said pintle may be inserted.

Wrapped around the pintle 20 is a coil spring 22, having one extremity 23 engaging the under surface of the body 10, and the other extremity 24 engaging the under surface of the member 15. By 50 this arrangement of the spring, the tension thereof normally acts to move the article engaging member 15 upwardly on said pintle toward the front face of the member 10. This upward movement, however, is limited by abutment lug 25, positioned 55 to arrest upward movement of the member 15, at

the time that the members 10 and 15 are in approximately right angular relation.

In practice, the support member 10 is attached to the wall W, or other support by means of the screw 12, and while so attached the support member 15 will normally lie in an approximately right angular position with respect to the wall and the member 10. To support a broom, mop, brush or any other device having a handle, said handle is passed upwardly through the opening 17 so that the article will bear downwardly on member 15, whereupon the weight of the article will move the support member downwardly on the pivotal support, said movement being yieldably resisted by the spring 22. Then by engaging opposite portions of the edge of the opening 17 with a downward pull on the handle the frictional engagement of said edge portions with the handle will hold the article firmly suspended. Such downward movement continues until the 65 lower end of the handle of the supported article engages the adjacent portion of the wall surface, whereupon further downward movement of the support member 15 is arrested, and the article is firmly supported, as above stated, with the 70 lower end thereof engaging the wall in a manner which will prevent swinging. To disengage, it is only necessary to grasp the handle of the article and move it upwardly. As soon as said member 15 is relieved of the weight of the article, the 75 spring will cause the member 15 to move upwardly to its horizontal position, thereby releasing member 15 from the frictional grip of the edge of the opening 17, and permitting free removal of the suspended article and leaving member 15 in 80 position for ready engagement when desired to again suspend the article.

In the form of the invention illustrated in Figures 4, 5 and 6, the device is constructed of wire parts bent into the desired form. Referring to 95 said figures, the support member consists of a body formed of a piece of wire 30 bent to provide loops 31, and arm-like portions 32, the extremities of which are bent to provide spaced-apart hinge eyes 33. The loops 31 are so arranged that 100 the device may be secured to the wall or other support by means of screws passed through said loops.

The article-engaging member is also constructed of a single piece of wire 34, bent to provide 105 an article-engaging loop 35, the end portions of which are bent laterally to provide hinge pintles 36. The wire at one of said pintles is continued and bent back to form a stop member 37, positioned to abut against one of the arms 32, and 110

the extremity of said stop arm is bent forwardly to provide a spring-engaging finger 38. A suitable spring connects said spring finger with one of the loops 31 so that the tension of said spring 5 normally maintains the device with the article-engaging member in horizontal position, pivotal movement in an upward direction being limited by stop 37 engaging the adjacent arm 32. The operation and functions of the device are identical with those described in connection with the structure illustrated in Figures 1, 2 and 3.

The advantages of the invention will be readily understood by those skilled in the art to which it belongs. It will be particularly noted that an 15 exceedingly simple and inexpensive device is provided, so constructed and arranged that it may be attached to a wall or other supporting surface, and while engaged with a broom, mop, brush or other device will yieldably sustain the same by 20 frictional engagement therewith, so that it will be held steadily and conveniently accessible.

It is to be understood that although the invention has been particularly described in connection with brooms, brushes and mops, it is not 25 limited in its use to supporting of these articles, but is capable of use in supporting various other articles and devices equipped with handles.

Having thus explained the nature of the invention and described an operative manner of constructing and using the same, although without attempting to set forth all of the forms in which it may be made, or all of the forms of its use, what is claimed is:—

1. A supporting device of the character described comprising a support-member formed of wire having its extremities provided with hinge eyes, an article-engaging member also constructed of wire and having bent pintle portions engaging said eyes, one of said pintle portions having 35 a finger-like extension, a spring connected with said extension and with said support-member, and complementary stop means carried by said members for limiting pivotal movement of the support-member in one direction under the tension of said spring.

2. A supporting device of the character described comprising a support-member formed of a piece of wire having arm-like end portions, the extremities of which are provided with hinge eyes, 50 an article-engaging member also constructed of a piece of wire having pintle portions engaging said eyes, one of said pintle portions having an abutment-member extended across one of said arm-like portions of the support member and terminating in an angular finger, and a spring connecting said finger with said body member.

3. A supporting device of the character described comprising a support member adapted

to be fixedly attached to a supporting surface and having a depending lower portion forming hinge ears, an article-engaging member having its rear portion provided with complementary hinge ears pivotally connected to the first mentioned hinge ears, and means normally acting to yieldably move the article-engaging member in one direction on said pivotal connection, one of said members having a portion of its body bent over to form an integral stop member abutting against the other member to limit pivotal movement of the article-engaging member in one direction.

4. A supporting device of the character described comprising a plate-like support member having a cut-away recess-portion provided with end walls forming hinge ears, an article-engaging member having its rear edge extended into said recess, said rear edge having hinge ears lying between the first mentioned hinge ears, a pivot pin connecting said hinge ears, a spring normally acting to move said article-engaging member in one direction, and stop means in a plane between said hinge ears to limit movement of the article-engaging member under tension of said spring.

5. A supporting device of the character described comprising a plate-like support member having a cut-away recess-portion provided with end walls forming hinge ears, an article-engaging member having its rear edge extended into said recess and having hinge ears lying between the first mentioned hinge ears, a pintle pivotally connecting said hinge ears, and a spring encircling said pintle and normally acting to move said article-engaging member in one direction, said support member having an integral stop lug at its lower edge portion positioned to overhang said article-engaging member, said hinge pintle and said spring being normally concealed from view.

6. A supporting device of the character described comprising a plate-like member having angular side edges and a cut-away recess-portion at its lower edge provided with end walls forming hinge ears, an article-engaging member of plate-like form also having angular side edges and having its rear edge extended into said recess and provided with hinge ears complementary to the first mentioned hinge ears, means pivotally connecting said hinge ears, a spring normally acting to move the article-engaging member in one direction, said spring and said hinge connecting means being so positioned as to be normally concealed by the side portions of the supporting plate and the article engaging member, and stop means in a plane between the hinge ears and so positioned as to engage the rear portion of the article engaging member to limit pivotal movement thereof.
